UNITED STATES PATENT OFFICE.

ISRAEL BLOOM, OF DENVER, COLORADO.

ADJUSTABLE CURTAIN ROD.

1,424,444.

Specification of Letters Patent. Patented Aug. 1, 1922.

Application filed February 21, 1921. Serial No. 446,559.

To all whom it may concern:

Be it known that I, ISRAEL BLOOM, a citizen of the United States, residing at the city and county of Denver and State of Colorado, 5 have invented certain new and useful Improvements in Adjustable Curtain Rods; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 The object of this invention is to provide a curtain rod which may be adjusted both as to length and as to position with respect to the window frame.

Briefly, the invention comprises a pair of 20 curtain supporting arms adjustably connected to each other and mounted upon plates adapted to be fixed to the sides of the window frame. Each arm is controlled by a spring which tends to urge it outward and 25 downward, means being provided to hold the arms against the tension of the springs in adjusted position.

In the drawings:

Fig. 1 is a front elevation of the rod in 30 use;

Fig. 2 is a side elevation;

Fig. 3 is an elevational detail; and

Fig. 4 is a detail in plan.

The window frame is indicated in the 35 drawings at 10 and to each side thereof an elongated strip 12 is secured by means of nails or the like 14. A bracket 15 is adapted to be mounted upon each strip 12 by means of pins 16 adapted to enter holes in the 40 strips 12 provided for the purpose. The reversely bent end 18 at each end of the curtain supporting rod 20 is journaled in the forward portion 115 of the respective bracket 15 and is provided adjacent its innermost 45 part and inside of the bracket 15 with a ratchet 24. Each reversely bent end is connected with the rod 20 by a curved connecting portion indicated at 22. A spring 25 is coiled about said end 18 and has its tip secured in the bracket 15, as indicated at 50 26 in Figure 2. The opposite end of the spring extends outwardly in the form of a loop 28 which bears upon the curved portion 22 of the rod 20, the spring returning thence 55 toward the middle of the device to provide an elongated curtain engaging rod 30 whose

extremity is in the form of a curved finger 32 adapted to fit over the curved members of the device to assist in retaining a curtain.

By the above construction, the arms 20 60 tend to move downward under the influence of the springs 25, but this movement is controlled by means of a dog 35 having an offset finger 36 which projects through an opening 38 in each bracket 15, the opposite end 65 of the dog 35 being secured to the bracket as by soldering, as indicated at 40. The normal position of each spring dog 35 is to engage the respective ratchet 24 to prevent downward movement of the respective curtain supporting arm 20. Each free end of each dog 35 may be removed from engagement with the ratchet 24 by pressing said free end downward, the offset projection 36 moving in the slot 38. With 70 this construction, the arm 20 may be set in a horizontal position, or may be swung upward and rearward toward the casing 10 or downward and rearward, as may be desired, the adjustment being maintained by 75 the dogs 35.

There is a pair of opposed supporting arms 20, a spring 42 being secured to the end of one arm 20, the opposite end of said spring 42 being secured at 44 to a sleeve 46 85 into which said end of the arm 20 projects. The opposed end of the other arm 20 is provided with a pin 48 adapted to travel in a longitudinally-extending slot 50 in said sleeve 46, short bayonet slots 52 extending 90 laterally from the slot 50 to receive the pin 48 for purposes of adjusting the length of the pair of arms 20 and for retaining the pin 48 in position in one of said bayonet slots 52.

In using the device, the strips 12 are secured to the opposite sides of the window frame. The pin 48 is set in one of the slots 52 so as to give a length slightly less than the width of the window frame 10. The 100 parts 20 are then separated slightly from one another by stretching the spring 42, and the brackets 15 are mounted in position upon the strips 12 with the pins 16 in the holes in said strips above described. The bayonet 105 slots 52 prevent further elongation of said arms 20, except by stretching of said spring 42. The rods 20 are then adjusted by swinging them upward or downward, as desired. The spring arms 30 are then lifted and the 110 lace curtain is slipped over the rods 20 to the required position, said spring arms 30 be-

ing allowed to fall upon the rods 20 and engage the curtain so as to securely retain the same.

By this construction it will be seen that 5 means has been provided which may be readily adapted to any window frame, and which may be swung outward sufficiently to hold a lace curtain out from the window frame far enough to avoid a roller shade also 10 secured to said frame.

I claim:

1. A curtain supporting device comprising in combination, a pair of brackets, a curtain rod having its ends reversely bent 15 and pivotally connected to said brackets, resilient means tending to move said rod in one direction about its pivots, and positive means opposing the action of said resilient means.
20. 2. A curtain rod having reversely bent ends, a bracket at each end thereof, a ratchet secured to each end of said rod, a dog mounted on each bracket and adapted to engage the respective ratchet, a spring controlling said rod to urge the ratchets against the dogs.
25. 3. A curtain rod having reversely bent ends, a bracket at each end thereof, a ratchet secured to each of the reversely bent ends, a dog mounted on each bracket and adapted to engage and cooperate with the corresponding ratchet, a spring having one end secured to the bracket and a portion surrounding

the reversely bent end of the rod, the other end of the spring resting on the upper side 35 of the rod and extending longitudinally thereof for the purpose of holding the curtain in place.

4. A curtain supporting device comprising a rod, a bracket in which each end of 40 said rod is journaled, said ends being reversely bent where they enter said brackets, a ratchet mounted on each of said reversely bent ends, a spring dog on each bracket to engage the respective ratchet, and a spring 45 mounted upon each reversely bent end and engaging said rod and the respective bracket to urge the ratchet against the dog.

5. A curtain supporting device comprising a rod, a bracket in which each end of 50 said rod is journaled, said ends being reversely bent where they enter said brackets, a ratchet mounted on each of said reversely bent ends, a spring dog on each bracket to engage the respective ratchet, and a spring 55 mounted upon each reversely bent end and engaging said rod and the respective bracket to urge the ratchet against the dog, each spring having an extension running inwardly along the rod and longitudinally 60 thereof to engage a curtain to retain the same between the rod and said spring extensions.

In testimony whereof I affix my signature.

ISRAEL BLOOM.
